LIQUID DISPENSING DEVICE

Raymond D. Champion, San Gabriel, and Lyle E. Fry, Los Angeles, Calif.

Application June 25, 1941, Serial No. 399,624

2 Claims. (Cl. 221—102)

This invention relates to liquid dispensing devices and has for an object the provision of a fountain tooth brush carrying its own reservoir for detergent and characterized by improvements in constructional details which adapt it for use with liquid dentifrice.

A more detailed object in this connection is the provision of a fountain tooth brush in the handle of which is provided a reservoir for liquid dentifrice, and which carries a simple, compact, and yet efficiently operating pumping mechanism the actuation of which results in forcing a suitable quantity of the liquid to the bristles of the toothbrush.

A further object of our invention is to provide means for sealing the outlet from the pumping mechanism and thereby positively preventing escape of the dentifrice except when the pumping mechanism is actuated.

A still further object is to provide a fountain toothbrush of the general character indicated, which is of such simple design that its cost of manufacture is low and it has little tendency toward becoming worn, broken, or otherwise incapacitated for useful service, which is of attractive design, and which lends itself readily for quantity production with all but the actual bristles thereof constructed of one of the molded plastics currently proving so popular.

The invention possesses other objects and valuable features, some of which, with those enumerated, will be set forth in the following description of the preferred embodiment of our invention illustrated in the drawing accompanying and forming part of the specification. It is to be understood that we do not limit ourselves to the showing made by the said drawing and description, as we may adopt variations of the preferred embodiment within the scope of our invention as defined by the claims.

Referring to the drawing:

Figure 1 is a perspective view of a fountain toothbrush embodying the principles of the present invention.

Figure 2 is a longitudinal, medial, vertical sectional view.

Figure 3 is a transverse sectional view, the plane of section being indicated by the line 3—3 of Fig. 2 with the direction of view as indicated.

Figure 4 is a fragmentary view similar to Fig. 2 but showing the reciprocable head and the pump part thereby moved to the outer end of their stroke.

Specifically describing the preferred embodiments of our invention, our improved fountain

toothbrush comprises the handle portion 6, the shank 7, and bristles 8 mounted in the conventional manner upon the outer end of the shank 7. The shank 7 is of tubular construction, having a bore 9 extending longitudinal thereof with the outer end of the bore 9 terminating in an outlet 11 adjacent the base of the bristles 8 as best shown upon Fig. 2 and and Fig. 4.

The handle portion 6 of our toothbrush comprises an enlarged end 12 on the shank 7, and a head 13 reciprocates thereupon. For this purpose the enlarged end 12 is provided with a slightly reduced cylindrical portion 14 and the associated end of the head 13 is fitted to the cylindrical portion 14 sufficiently tightly to assure against leakage therebetween and yet permit the head 13 to reciprocate upon the cylindrical portion 14.

For the purpose of determining the length of strokes to which the head 13 can be reciprocated upon the shank 7 we have provided a pin 16 rigid with the cylindrical portion 14 of the shank 7 and disposed slidably within an L-shaped slot 17 in the skirt 18, i. e., that portion 20 of the head 13 which is slidably engaged upon the cylindrical portion 14 of the shank 7. One leg 19 of the slot 17 extends parallel to the axis, i. e., longitudinally of the toothbrush, whereas the other leg 21 of the slot 17 extends transversely with respect thereto, i. e., circumferentially of the skirt 18. However, instead of being accurately at right angles with the leg 19 we prefer that the leg 21 be arranged at a slight slope so that its outer end is slightly further 25 away from the extreme associated end of the head 13 so that when the pin 16 is disposed within the leg 21 of the slot and then the head 13 turned with respect to the shank 7 a leverage will be developed between the pin 16 and the head driving the head to the left as viewed 30 upon Figs. 1, 2, and 4.

Upon the outer end of the head 13 a cylindrical extension 26 is secured as by threads 27. The outer end 28 of the cylindrical extension 26 35 is closed; and inasmuch as the extension 26 is hollow it is adapted to serve as a reservoir to store a supply of liquid dentifrice 29. The threaded engagement between head 13 and the reservoir 26 permits removal of the latter for the 40 purpose of replenishing the supply of liquid 29.

The head 13 also is of hollow construction and has a spider 31 through the aperture 32 of which the liquid 29 is permitted to flow through the bore 33 of the head 13. The spider 31 carries a 45 structurally disposed plunger 34, the end of

which is fitted to and is adapted to enter a compression chamber 36 in the proximal end of the shank 7, when the head 13 is reciprocated to the inner end of its stroke, i. e., moves to that position in which it is illustrated in Figs. 1 and 2.

The bore 9 of the shank 7 communicates with the compression chamber 36 through an enlarged portion 37; and a rod 38 carried by and extending axially from the plunger 34 lies within this enlarged portion 37 of the bore 9. The parts are so proportioned and arranged that although the rod 38 is less in diameter than is the enlarged portion 37 of the bore 9, thus permitting liquid to flow through the enlarged portion 37 and the rod 38, the extreme end of the rod 38 is adapted to engage the shoulder 41 which terminates the enlarged portion 37, such engagement occurring in the head 13 as it is reciprocated to the extreme inner end of its stroke. Accordingly the end of the rod 38 and the shoulder 41 cooperate to function as a valve and valve seat respectively; and inasmuch as this valve seat 41 is disposed closely adjacent the outlet 11 of the bore 9, seating of the end of the rod 38 against the shoulder 41 effectively prevents leakage of liquid through the outlet 11 when such engagement is completed. Through indication of the sealing of the outlet 11 of the bore 9 proved in actual use that it permits carrying the toothbrush of our invention filled with dentifrice and ready for use, in the pocket or in luggage and with perfect impunity.

In order to supply dentifrice to the bristles 8 of the brush it is necessary only to reciprocate the head 13 with respect to the shank 7 one or more times, depending upon the amount of dentifrice desired. When the head 13 is withdrawn to the Fig. 4 position the end of the plunger 34 is removed from the compression chamber 36 permitting dentifrice 23 to flow into the compression chamber. Then when the head 13 is pushed back toward the shank 7 the end of the plunger 34 then enters the compression chamber 36 whereupon continuous motion of the head 13 forces the dentifrice which has been entrapped within the compression chamber 36 through the bore 9 and out the bristles 8 by the outlet 11. Principally the parts are so proportioned that a single operation of the pumping mechanism in the manner described will supply a quantity of liquid dentifrice capable of meeting normal requirements. However, if the operator desires a greater quantity of dentifrice upon the bristles he can reciprocate the head 13 as many times as desired.

After the desired amount of dentifrice has been supplied to the bristles 8 in the manner described the operator should rotate the head 13 upon the shank 7, thus causing the pin 16 to enter the obliquely arranged leg 21 of the slot 17. As hereinabove explained such relative rotation between the parts will develop a wedging action forcing the head tightly onto the shank 7 and insuring

tight seating of the end of the rod 38 against its associated valve seat 41, thus making doubly sure that there will be no inadvertent leakage out of the port 11 until the pumping mechanism is again released and intentionally reciprocated.

We claim:

1. In a liquid dispenser of the character described, a tubular shank, the bore of said shank having an outlet communicating with the exterior of said shank, a head reciprocably mounted on one end of said shank in telescopic relation therewith and having a cavity therein adapted to receive liquid detergent, one end of said bore terminating in a compression chamber opening to the associated end of said shank to communicate with said cavity, a plunger complementary to said chamber and carried by said head in position to enter said chamber and, as said head approaches the inner end of its stroke, compress liquid entrapped therein and thereby force liquid through said bore to said outlet, means within said bore presenting a valve seat adjacent said outlet, a rod carried by said plunger and extending therefrom through said bore to engage said seat when said head reaches said end of its stroke, and means for releasably locking said head with said rod in sealing engagement with said seat.
2. In a liquid dispenser of the character described, a tubular shank, the bore of said shank having an outlet communicating with the exterior of said shank, a head rotatably and reciprocably mounted on one end of said shank in telescopic relation therewith and having a cavity therein adapted to receive liquid detergent, said bore terminating in a compression chamber opening to the associated end of said shank to communicate with said cavity, a plunger complementary to said chamber and carried by said head in position to enter said chamber and, as said head approaches the inner end of its stroke, compress liquid entrapped therein and thereby force liquid through said bore to said outlet, means within said bore presenting a valve seat adjacent said outlet, a rod carried by said plunger and extending therefrom through said bore to engage said seat when said head reaches said end of its stroke, said head having a slot in that portion thereof which is in engagement with said head, said slot including a portion extending longitudinally of said head and a portion extending circumferentially thereof, and a pin rigid with said head and slidably disposed within said slot, said circumferential portion of said slot being aligned with said pin when said head is at said inner end of its stroke whereby said head is adapted for rotating to enter said pin into said circumferential portion of said slot and thereby lock the parts with said rod in sealing engagement with said seat.
